CLAIM

The ornamental design for a display screen with graphical user interface, as shown and described.

DESCRIPTION

The patent or application file contains at least one drawing executed in color. Copies of this patent or application publication with color drawing(s) will be provided by the Office upon request and payment of the necessary fee.

FIG. 1 is a front view of a first embodiment of a display screen with graphical user interface of the present invention.

FIG. 2 is a front view of a second embodiment thereof.

FIG. 3 is a front view of a third embodiment thereof.

FIG. 4 is a front view of a fourth embodiment thereof.

FIG. 5 is a front view of a fifth embodiment thereof.

FIG. 6 is a front view of a sixth embodiment thereof.

FIG. 7 is a front view of a seventh embodiment thereof; and,

FIG. 8 is a front view of an eighth embodiment thereof.

(Continued)

The features shown in broken line depict environmental subject matter only and form no part of the claimed design.
